ATTORNEY

UNITED STATES PATENT OFFICE.

JAMES M. BROWN, OF PITTSBURGH, PENNSYLVANIA, ASSIGNOR TO WESTINGHOUSE ELECTRIC & MANUFACTURING COMPANY, A CORPORATION OF PENNSYLVANIA.

INSULATOR.

Application filed December 14, 1918. Serial No. 266,704.

To all whom it may concern:

Be it known that I, JAMES M. BROWN, a citizen of the United States, and a resident of Pittsburgh, in the county of Allegheny and State of Pennsylvania, have invented a new and useful Improvement in Insulators, of which the following is a specification.

My invention relates to insulators and particularly to insulators for supporting bus-bars or similar conductors.

One object of my invention is to provide a hollow insulator that shall have adjustable and lockable bus-bar supporting means and means for simply and effectively securing the same to one end of the insulator.

Another object of my invention is to provide a novel single means for reinforcing a hollow insulating pillar and for accurately positioning the latter on its supporting means.

In a co-pending application, Serial No. 266,720 filed Dec. 14, 1918, by Karl C. Randall and assigned to the Westinghouse Electric & Mfg. Company, is disclosed a hollow insulator having both its inner and outer surfaces conforming to a dielectric field.

In practicing my invention, I provide bus-bar holding means that may be adjusted universally with respect to an insulator of the above indicated character, means for locking the bus-bar in adjusted position and a single means for reinforcing the pillar and accurately positioning the same on a suitable base.

Figure 1 of the accompanying drawings is a plan view, partially in section and having the immediate bus-bar holding structure removed for the sake of clearness, of a device embodying my invention, and Fig. 2 is a longitudinal sectional view of the same, partially in elevation and as viewed in the direction of a bus-bar.

A hollow insulating member 1, shown as substantially of bowl shape but that may be of other shapes, and preferably formed of porcelain, is provided with inwardly and outwardly projecting flanges 2 and 3 at its outer and inner ends, respectively.

A metal ring or frame 4 having a flange 5, for co-operation with the flange 3, and apertured lugs 6, is secured to a base plate or ring 7 by screws 8 that extend through the lugs 6 and into the plate 7. Bolts 9, having co-operating nuts 10, extend through the plate 7 and secure the same to a suitable

support, not shown. A cushioning ring 11, of felt or other suitable material, is disposed between the flanges 3 and 5.

A preferably relatively-thin-walled metal member 12, of substantially cup-shape, has its main body portion extending into and closely engaging one end of the member 1 and an outwardly-projecting flange 14 nested between the members 1 and 7, in a recess in the outer face of the latter. The member 12 assists in mechanically reinforcing the member 1 against lateral stresses at its point of support and serves as a centering means therefor. Clamping members 16 and 17 are disposed at the outer end of the member 1, on the outside and inside, respectively, of the flange 2 and are joined together by bolts 18. A resilient cushioning washer 19, of felt or other suitable material, is interposed between the flange 2 and the member 17.

An interiorly-threaded centrally-disposed tubular portion 20, of the member 16, supports an adjustable screw-threaded stud 21 that may be locked in adjusted position by a set screw 22 extending through the portion 20. A pair of supplemental clamping members 23, between which a bus-bar 24 is rigidly clamped, as by co-operating bolts 25 and nuts 26, are rigidly secured to the outer end of the stud 21. A plurality of pairs of longitudinal ribs 27, on the tubular portion 20, serve, not only as spacing and centering means for the members 16 and 17 with respect to the member 1, but also as reinforcing means for the portion 20 against the stresses imposed by the bolts 18 that are disposed between the ribs of the respective pairs of ribs 27.

Adjusting screw-bolts 28 extend through the member 16 to the outer surface of the flange 2 and permit the rigid and accurate correlation of the insulator members, regardless of irregularities in the members and of any deviation from true parallel in the relation between the planes of the bus-bar 24 and the member 1.

By the above described construction a hollow refractory bus-bar insulator, of the pillar type, is adequately protected against bending-moment stresses at its base, may be quickly and accurately assembled and facilitates the accurate and effective universal adjustment of the bus-bar which it is adapted to support. By loosening the screw 22 and turning the stud 21 and by manipulat-

ing the screw-bolts 28, the bus-bar 24 may be adjusted towards, from or to any angular relation with respect to the member 1.

While I have shown and described a particular form of my invention, changes may be effected therein, without departing from the spirit and scope thereof, as set forth in the appended claims.

I claim as my invention:

- 10 1. A bus-bar insulator comprising a tubular insulating member having an inwardly-projecting annular flange adjacent to the outer open end thereof; a centrally-apertured annular metal member and a discoidal metal member disposed on the outside and on the inside, respectively, of said flange, a bus-bar supporting member longitudinally adjustably mounted on said annular member in the aperture thereof, and a plurality of bolts equally spaced about said supporting member extending through the open end of the insulating member for connecting said metal members and clamping the same uniformly against said flange 25 around said bus-bar supporting member.

2. A bus-bar insulator comprising a tubular insulating member having an inwardly-projecting annular flange adjacent to the outer open end thereof, a centrally-apertured annular metal member and a discoidal metal member disposed on the outside and on the inside, respectively, of said flange, a bus-bar supporting member longitudinally adjustably mounted on said annular member in the aperture thereof for varying the position of a bus-bar relative to the insulator, and means extending through the open end of the insulating member between the supporting member and the flange for connecting said metal members and clamping the same uniformly against said flange.

3. A bus-bar insulator comprising a tubular insulating member having an inwardly-projecting annular flange adjacent to the outer open end thereof, a centrally-apertured metal member disposed on the outside of said flange and having a tubular reinforcing portion around said aperture extending into the opening in the insulating member, a discoidal metal member on the inside of said flange having a central recess, a bus-bar supporting member longitudinally adjustably mounted on said outer metal member in the aperture and tubular portion thereof and movable into and from the recess in said discoidal member to vary the

position of a bus-bar relative to the insulator, and means extending through the open end of the insulating member between the supporting member and the flange for connecting said metal members and clamping the same uniformly against said flange. 60

4. An insulator comprising a tubular insulating member having an inwardly-projecting portion at one end thereof, transverse metal members disposed on opposite sides of said projecting portion, one of said metal members being provided with an internally-threaded tubular boss having longitudinally extending outer ribs, bolts disposed intermediate said ribs for connecting said metal members, a threaded stud disposed in said internally-threaded portion, means on the outer end of said stud for supporting a conductor and a set screw extending through the wall of said internally-threaded portion for locking said stud in position. 70

5. A bus-bar insulator comprising a tubular insulating member having an inwardly-projecting annular flange adjacent to the outer open end thereof, a centrally-apertured metal member disposed on the outside of said flange, means for adjusting said metal member parallel to the longitudinal axis of the insulator, a discoidal metal member on the inside of said flange, a bus-bar supporting member longitudinally adjustably mounted on said outer metal member in the aperture thereof to vary the position of a bus-bar relative to the insulator, and means extending through the open end of the insulating member between the supporting member and the flange for connecting said metal members and clamping the same uniformly against said flange. 90

6. A bus-bar insulator comprising an insulating member having an end opening and an inwardly-projecting annular flange adjacent to said opening, and conductor-supporting means including a pair of transverse metal members clamped longitudinally against opposite sides of said flange and a member for disposition on one of said metal members partially inside and partially outside said insulating member at said opening for adjusting movement in the direction of the longitudinal axis of the insulator. 100

In testimony whereof, I have hereunto subscribed my name this 30th day of Nov. 1918.

JAMES M. BROWN.
